US00D907929S

(12) **United States Design Patent** (10) **Patent No.:** **US D907,929 S**
(45) **Date of Patent:** **** Jan. 19, 2021**

(54) **THERMOSET SURFACE MATERIAL WITH ORNAMENTATION**

(71) Applicant: **DUPONT SAFETY & CONSTRUCTION, INC.**, Wilmington, DE (US)

(72) Inventor: **Massimo Fucci**, Milan (IT)

(73) Assignee: **DUPONT SAFETY & CONSTRUCTION, INC.**, Wilmington, DE (US)

(**) Term: **15 Years**

(21) Appl. No.: **29/708,093**

(22) Filed: **Oct. 3, 2019**

(51) LOC (13) Cl. **05-06**

(52) U.S. Cl.

USPC **D5/47; D5/44**

(58) **Field of Classification Search**

USPC ... D5/1, 3, 4, 43, 44, 47, 53, 56, 58, 59, 61, D5/62, 63, 99; D6/610, 613, 616; D19/5; D20/22, 27; D25/138; D32/57 CPC .. A61F 2013/00153; A61F 2013/53916; A61F 2013/0068; A61F 2013/530562; B44F 3/00; B44F 7/00; D03D 3/00; D21F 1/0027; D21H 27/02; F41H 3/02

Primary Examiner — Karen S Acker

CLAIM

The ornamental design for a thermoset surface material with ornamentation, as shown and described.

DESCRIPTION

The file of this patent contains at least one drawing/photograph. Copies of this patent with color drawing(s)/photograph(s) will be provided to the Office upon request and payment of the necessary fee.

The sole FIGURE is a top plan view of a thermoset surface material with ornamentation, showing my new design. The broken lines surrounding the figure depict the boundaries of the claim and form no part thereof.

**1 Claim, 1 Drawing Sheet
